(57) **CLAIM**

The ornamental design for a handle, as shown and described.

DESCRIPTION

In a preferred embodiment, the nature of this product is a handle for a plumbing fitting such as a shower water control or a faucet.

FIG. 1 is a right, top, front perspective view of a handle embodying my new design;

FIG. 2 is a top plan view thereof;

FIG. 3 is a front elevational view thereof, the left and right side elevational views thereof being identical to the front view shown; and,

FIG. 4 is a bottom plan view thereof.

The broken line representations of post structure in FIGS. 1 and 3-4 are for the purpose of illustration only, and forms no part of the claimed design.
